CLAIM

The ornamental design for an exercise stepper as shown and described.

DESCRIPTION

FIG. 1 is a top, right front perspective view of an exercise stepper, showing my new design;

FIG. 2 is a bottom, left back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines in the drawings depict portions of the exercise stepper that form no part of the claimed design.

1 Claim, 6 Drawing Sheets(56)
